UNITED STATES PATENT OFFICE

JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

MECHANISM FOR MAKING BOLTS.

1,119,491.

Specification of Letters Patent.

Patented Dec. 1, 1914.

Application filed March 6, 1911. Serial No. 612,439.

To all whom it may concern:

Be it known that I, JOHN R. BLAKESLEE, a citizen of the United States, and a resident of Cleveland, county of Cuyahoga, and State of Ohio, have invented a new and useful Improvement in Mechanism for Making Bolts, of which the following is a specification, the principle of the invention being herein explained and the best mode in which I have contemplated applying that principle, so as to distinguish it from other inventions.

In the upsetting of bars or rods to form heads onto bolts or like articles, the practice heretofore has been to employ a heading tool wherein the concavity corresponds exactly with the form and dimensions of the head. The rod or bar is then advanced between the gripping dies wherein it is held just the proper distance to leave enough metal projecting to fill this concavity, when the header is forced up against said gripping dies. Since the shape or transverse section of the head does not correspond with that of the body of the bar, where, for example, the head is square or hexagonal and the body round, there is a tendency for the metal, as it is thus upset and compressed within the die space, to escape from between the subsequently contacting faces of the heading tool and gripping dies and thus to form a fin around the lower edge of the head which requires to be trimmed off later. Not only does the extra operation thus involved in forming a finished bolt, or like article, increase the expense, but there is also the possibility that the die-space in the heading tool will not be completely filled, thus leaving the head misshapen. By the present invention, however, I have provided improved mechanism for upsetting the end of a bar or rod to form a head thereon, whereby the tendency to form fins, or in other words, for the metal to escape from between the gripping dies and heading tool, is substantially entirely eliminated, thus rendering it possible quickly and by a single operation to form a complete and satisfactory head.

To the accomplishment of these and related ends, said invention, then, consists of the means hereinafter fully described and particularly pointed out in the claims.

The annexed drawings and the following description set forth in detail certain mecha-

nism embodying the invention, such disclosed means constituting, however, but one of various mechanical forms in which the principle of the invention may be used.

In said annexed drawings:—Figure 1 is 60 a plan view of so much of a heading machine as is required to illustrate the present invention; Fig. 2 is a central vertical section thereof taken on the line 2—2, Fig. 1; Fig. 3 is a front elevational view of the heading tool; while Figs. 4 and 5 illustrate in more or less diagrammatic fashion, different operative positions of said heading tool with relation to the work being operated upon.

It has not been deemed necessary to illustrate the general frame, or bed 1, upon which the several parts concerned in the present invention are supported other than is involved in the sectional illustration of 75 Fig. 2; the parts in question include, then, two relatively transversely movable gripping dies 2 which have their inner faces formed with complementary recesses 3 adapted to receive and grip the work, when 80 said dies are forced together. Movable longitudinally of the line of feed of the work or, in other words, transversely of such direction of relative movement of the dies 2, is the header slide 4 shown in fully advanced position in Figs. 1 and 2. This header in the present improved construction is provided with a forwardly extending bracket 5 within which is reciprocably mounted the heading tool 6. Movement of 85 said tool relatively to the head is limited by stops in the form of projecting lugs 7 that fit in corresponding longitudinal slots 8 in the extension 5 in question. A spring 9 disposed within a recess 10 in the header 95 slide behind the tool 6, tends to advance the same into its forward limiting position, while contrariwise a catch 11 mounted on the upper face of the slide, is adapted to engage the correspondingly disposed stoppin 7 on the tool to retain the latter in its retracted position.

Catch 11 is mounted on an oscillatory shaft 12 that projects to one side of the head and there bears a rock-arm 13 provided with 105 a lateral projection at its free end. A cam 14 lies in the path of travel of the projection and the latter rides up on the upper face of the cam during retraction of the slide and thus rocks the catch 11 from engagement 110

2

with stop 7, so that tool 6 may be moved into forward position by spring 9. The body of said tool is bored out to receive two die members 15 onto which it is then shrunk so as to securely hold the same in place. A passage 16, however, is desirably left between these members and the tool body for circulating water or other cooling fluid around the assembled die. These die members form an opening 17 of transverse sectional shape corresponding with that of the head which it is desired to form. As illustrated (see Fig. 3), such opening and head are square, but the opening may be of hexagonal or other shapes. Lying within the bore provided between said die-members is a close-fitting plunger 18, the rear end of which is secured in the body of the slide so as to be held against longitudinal movement; the heading tool, however, is reciprocable relatively to said plunger, so that, while in the retracted position of the tool, the plunger extends almost to the forward end of the bore, in the advanced position of said tool relatively to the head (this position being assumed upon the retraction of the head), said plunger lies at some distance to the rear, as shown in Fig. 4. Such Fig. 4 represents in effect the inoperative position of the parts, that is, the position which they assume just prior to the forward movement of the head. The relative position of the plunger within the die opening of the heading tool remains unchanged until the latter is brought up against the face of the gripping dies, as illustrated in Fig. 5. Any further advance of the head will now force the plunger forwardly within said tool, until finally it reaches the limiting position of Fig. 2. The effect of this same movement is to compress the spring 9 behind the tool, forcing said tool into the head until it is locked by engagement of the catch 11 with the pin 7.

The general mode of operation of the mechanism illustrated for carrying on my improved method of heading bolts and the like should clearly appear from the foregoing description. It is to be noted, however, that by reason of the construction of such mechanism the projecting portion of the bar 20 which is to be upset is preliminarily entirely inclosed within the hollow heading tool; then the upsetting plunger, proper, advances in such projecting portion, forcing it down into the compass and shape it is designed to receive for the finished head. As a perfect inclosure, however, is provided, none of the metal thus be-

ing upset can escape, and as a result the head 60 has none of the objectionable fins or projections hereinbefore referred to.

The operation of the mechanism is obviously just as simple and expeditious as in the case of the prevailing type of construction and the adjustment of the machine for the formation of different kinds of heads substantially as readily effected.

Other modes of applying the principle of my invention may be employed instead of 70 the one explained, change being made as regards the mechanism herein disclosed, provided the means stated by any of the following claims, or the equivalent of such 75 stated means, be employed.

I therefore particularly point out and distinctly claim as my invention:—

1. In mechanism of the class described, the combination with dies for gripping the stock; of a reciprocable slide; a bracket secured to said slide and projecting toward said gripping dies, said bracket being provided with a longitudinal bearing and with a longitudinal slot; a heading tool reciprocably fitted in said bearing and adapted to 85 abut against said gripping dies, said tool having a bore adapted to inclose the stock and of the cross-sectional form desired; a pin secured to said tool and extending outwardly through said slot; resilient means 90 tending to advance said tool; a catch secured to the slide and adapted to engage said pin when the slide is in advanced position; means for releasing said catch during retraction of the slide and an upsetting plunger fixedly secured to said slide and reciprocably fitted in the bore of said tool.

2. In mechanism of the class described, the combination with dies for gripping the stock; of a reciprocable slide; a heading tool 100 reciprocably mounted on the slide and adapted to abut against the gripping dies, the tool having a bore adapted to inclose the stock and of the cross-sectional form desired; resilient means tending to advance 105 the tool; a catch secured to the slide and adapted to engage the tool when the slide is in advanced position; means for releasing the catch during retraction of the slide; and an upsetting plunger fixedly secured to the 110 slide and reciprocably fitted in the bore of the tool.

Signed by me this 4th day of March, 1911.

JOHN R. BLAKESLEE.
